Specification of Letters Patent. Patented Sept. 10, 1918.

Application filed June 14, 1918. Serial No. 239,937.

To all whom it may concern:

Be it known that we, OTIS R. HASTY and HARRY A. Atwood, citizens of the United States, residing at Elgin, in the county of 5 Kane and State of Illinois, and Milwaukee, in the county of Milwaukee and State of Wisconsin, respectively, have invented certain new and useful Improvements in Chairs, of which the following is a specification.

10 Our invention concerns various features of novelty and of structural and functional advantage in chairs, more especially, but not exclusively, in chairs of the typewriter style, having hinged, adjustable, spring-controlled, backs. One object of the invention is the production of a chair of this general 15 type in which the staff or bar carrying the back-rest or back proper is demountably assembled with its support and is held thereto by the adjusting means controlling the tension of the spring.

20 A further feature of the invention is the provision of a chair of such construction that it may be shipped with the back and its 25 staff detached from the remainder of the chair structure for economy in shipping space, the fastening means to secure these separate parts together being of such construction as to preclude their improper assembly and to assure their ready association 30 with ease and despatch. The elimination or avoidance of any slots in the wooden back staff avoids splitting of the latter, which weakness is likely to develop in chairs of 35 the mode of manufacture prior to the production of this improved style. The new chair uses an expansion as contrasted with a compression spring for the back, and such spring is disposed practically horizontally 40 beneath and close to the chair-seat behind its screw-threaded supporting shaft and hence is out of sight and in a position for most favorable performance of its yielding or cushioning functions. Furthermore, the 45 construction and combination of parts is such that there is no tendency for the catching or pinching of articles of clothing, such as a skirt, for example, and the chair is not rendered unusable if the spring happens to 50 break.

Simplicity in structure, effectiveness in action, ease of assembly, and certainty of correct association of parts, hidden disposition or location of the spring, avoidance of

slots in the back staff, economy in manufacture, and several other desirable objects are attained in the embodiment of this invention.

55 In order that the advantages of the formation and organization of the parts of the improved chair or the mode or way in which its elements are put together, as well as their operative capabilities, may be readily understood and appreciated we have illustrated in the accompanying drawings forming a part 60 of this specification, a simple desirable embodiment of the invention, and throughout the various views of these drawings like reference characters refer to the same parts.

65 In these drawings: 70

Figure 1 is an elevation of the chair;

Fig. 2 is a horizontal section on line 2—2 of Fig. 1;

Fig. 3 is a section on line 3—3 of Fig. 1 with the parts viewed in the direction indicated by the arrows; 75

Fig. 4 is an enlarged vertical section on line 4—4 of Fig. 3; and

Fig. 5 is a horizontal section on line 5—5 of Fig. 4. 80

85 Referring to these drawings it will be observed that the new and improved chair comprises a standard composed of a base 10 with a plurality of feet 11, 11, in association with a central, upright, threaded shaft 12, 85 adjustable as to height by any approved means. At its upper end this shaft has a seat-supporting spider including forwardly-projecting, radiating or diverging arms 13, 13, and a pair of approximately-parallel 90 rearwardly-extended arms 14 and 15, all of which are secured by screws to the underside of the chair-seat 16, arms 14 and 15 back of the central shaft having an integral cross-bar 17. At their rear ends these two 95 substantially-parallel, spaced spider-arms 14 and 15 have downwardly and rearwardly extended ears or lugs 18 and 19, between which a rocker-arm 20 is fulcrumed or hinged by means of two screws 21, 21, (Fig. 100 5) threaded into opposite sides of the arm and having bearings in cylindrical holes in the ears. This rocker-arm comprises two side-walls 22 and 23 connected together by a bottom-web 24 and a front-web 25 apertured at 26. The wooden staff or post 27 for the back-rest 28 is apertured at 29 in alignment with the hole 26, the lower end 105

of such staff being accommodated in the socket or recess formed by the rocker-arm walls with its front face bearing against the rear surface of web 25. This staff is held in 5 the socket by means of a clip 30 fastened by means of screws 31 to its front face and having a right-angle lip 32 fitted over the top edge of wall 25 and bearing against the upper portion of its front face, and the staff 10 is also maintained secured to such rocker-arm by means of a threaded rod 33 extended through the registering apertures 26 and 29 and provided at the back of the staff with a washer 34 and an adjusting or tension-controlling nut-handle 35, its front end beneath the chair-seat being in the form of a loop, eye, or hook, engaging the rear end of a coil expansion spring 36 whose other end hooks over cross-bar 17.

15 It will be appreciated, therefore, that the spring is behind the upright, threaded, seat-supporting shaft 12, is disposed horizontally directly beneath and close to the seat, is practically invisible, and directly connects the seat-supporting spider with the back-rest staff. The tension of such spring may 20 be easily and quickly varied by manipulation of the handle 35 which directly connects with the anchored spring through the threaded rod with which it coöperates. Thus, the strength of this spring cushion or spring pressure, which normally tends to swing the back-rest staff forwardly against the back of the chair's occupant, may be readily governed and controlled.

25 The appliance is also provided with stops to limit or restrict the forward and back swinging of the staff and its back-rest. The bottom edge of each ear 18 and 19 is recessed or cut away at 40 to supply front and rear shoulders 41 and 42 with which oppositely-extended lugs 43 on the rocker-arm co-act. These coöperating members limit the forward swing of the staff under 30 the action of the spring and also restrict its rearward rocking under the action of the occupant bearing and pressing against the back-rest carried by the staff. In case the spring should break, these shoulders still 35 perform their function and the chair need not be necessarily discarded until the spring is replaced by another.

Should it be desired to demount or remove the staff and back-rest for shipment or 40 other purposes, it is merely necessary to unscrew and remove the nut-handle 35 and withdraw the threaded rod 33, whereupon the staff can at once be lifted free from the rocker-arm socket, the clip 30 in no way 45 hindering such removal, but rather readily sliding off of the rocker-arm wall with which it is associated. Under normal circumstances, the strain put upon the upright staff is imposed thereon both through this clip and 50 also through the nut-handle, thus distrib-

uting the strain and eliminating its concentration which might, under some circumstances, tend to split the staff.

In order to avoid slotting this wooden staff to permit vertical adjustment of the 70 back-rest 28 which it carries, a metal slotted strap 70 is secured in an upright manner to the back-rest by screws 71, 71, such strap or bar having narrow side flanges 72, 72, overlapping the opposite edges of the staff 75 to prevent angular displacement of the rest. A bolt 73 has a squared shank 74 fitted and adjustable in the vertical slot 75 of the strap or bar, the threaded part of the bolt extending rearwardly through a hole 76 in the 80 staff, back of which it is provided with a tightening nut or handle 77. By this means slotting and weakening of the staff itself is avoided without losing the advantage of the vertical adjustment of the rest and holding 85 it in proper horizontal position.

To those skilled in this art it will be clear that many minor mechanical changes may be made in the structure presented without departure from the heart and essence of the invention and without the sacrifice of any of its substantial benefits and advantages.

We claim:

1. A chair having an adjustable back comprising in combination a standard, a seat mounted thereon, a back hinged on said standard, a coil expansion spring connected at one end to said standard, and screw-threaded means to adjust the tension of said 100 spring extended through said hinged back and including a demountable threaded handle the turning of which varies the spring tension and constituting the sole device preventing detachment of the back from the 105 remainder of the structure, substantially as described.

2. A chair having an adjustable back comprising a standard having a seat-supporting spider, a seat mounted on said spider, a hinged back, a spring connected at one end to said spider, means engaging the other end of said spring and having a screw-threaded shank extended rearwardly through a hole in the back, and a threaded handle 110 engaging said threaded shank and adapted to adjust the tension of said spring and demountably hold said back in place, substantially as described.

3. A chair having an adjustable back comprising in combination, a standard or base having a seat-supporting spider with two rearwardly-extending arms connected together by a cross-bar, a seat on said spider, a pair of spaced ears at the rear ends of 125 said arms, a rocker-arm hinged to and between said ears, a back-staff positioned between spaced walls of said rocker-arm, a clip secured to said staff overlapping the front of said rocker-arm, said ears and rocker- 130

- arm having coöperating means limiting the 5 rocking of said arm, a spring beneath the chair-seat close to and substantially parallel to its under face and having its front end connected to said spider cross-bar, a threaded rod extended through alined apertures in said rocker-arm and back-staff and engaging the rear end of said spring, and a threaded handle coöperating with said rod back of 10 said staff, whereby said handle adjusts the tension of said spring and constitutes the sole means preventing demounting said staff from said rocker-arm, substantially as described.
- 15 4. A chair having a hinged back comprising in combination, a chair-standard having a seat-support, a seat mounted on said support, a rocker-arm hinged to said seat-support, a chair-back staff coöperating with 20 said rocker-arm, a spring acting on said staff
- connected at one end to said seat-support, and means for adjusting the tension of said spring and also assisting in securing such staff to said rocker-arm, substantially as described. 25
5. A chair having a hinged back comprising in combination, a chair-standard having a central shaft equipped at its top with a seat-support, a seat mounted on the support, a rocker-arm hinged on said support, 30 a chair-back staff mounted on said rocker-arm, a substantially-horizontal spring disposed beneath said seat rearwardly of said shaft and having one end connected to said seat-support, means connecting said spring 35 to said rocker-arm and staff, and means to adjust the tension of said spring, substantially as described.
